UNITED STATES PATENT OFFICE.

EDWARD N. DICKERSON, JR., OF NEW YORK, N. Y.

WHEEL FOR ELECTRO-MAGNETIC LOCOMOTIVES.

SPECIFICATION forming part of Letters Patent No. 257,298, dated May 2, 1882.

Application filed January 5, 1881. (No model.)

To all whom it may concern:

Be it known that I, EDWARD N. DICKERSON, Jr., of the city, county, and State of New York, have invented a new and useful Improvement 5 in Wheels for Electro-Magnetic Locomotives, of which the following is a full, true, and exact description, reference being had to the accompanying drawing.

Locomotives have been operated by electro-
10 magnetism occasioned by electric currents con-
veyed to them upon the rails upon which they
run. Owing to the usual construction of such
wheels, it has been found very difficult to prop-
erly insulate the different parts of the mech-
15 anism from the rails and at the same time to
obtain a sufficiently durable and satisfactory
wheel.

My invention relates to the application to
such apparatus of wheels composed in part or
20 wholly of compressed paper, ordinarily known
as "papier-maché." Such wheels are well
known in the art for the purpose of deadening
the blow between the rail and the locomotive
or car, and are satisfactory and useful wheels.

25 In my apparatus, A represents generally an
electro-magnetic engine running upon rails R.
The engine or locomotive is supported upon
wheels W W W, the bodies B of which are com-

posed of paper, as shown. These wheels may
consist of the outer tire, C, the compression-
30 plates D, and the insulating-body B. The
electricity conveyed to the engine on the rails
R is taken from the wheels by springs S, bearing
against their surfaces, and is thereby con-
veyed to the engine. In this way no especial
35 apparatus for insulation is required, and a use-
ful and valuable wheel is employed.

I do not claim broadly the idea of insulat-
ing an electro-magnetic locomotive from the
rails upon which it runs; but
40

I do claim as my invention and desire to se-
cure by Letters Patent—

The combination of an electro-magnetic en-
gine or locomotive running upon rails, with
paper wheels supporting such locomotive upon
45 the rails, and provided with a metallic con-
ducting-tire and springs for conducting the
electricity from the track to the engine, while
at the same time the current is insulated from
the main frame of the locomotive, substan-
50 tially as described.

E. N. DICKERSON, JR.
